CECIL H. BOYULS, OF LOUISVILLE, KENTUCKY

STEAM FINISHER

Application filed July 5, 1928, Serial No. 290,617. Renewed August 27, 1930.

This invention relates to laundry machinery and has special reference to an ironing machine of the type known as a finisher.

More particularly the invention relates to 5 a steam heated ironing finisher.

In the ironing of clothes it frequently occurs that the mangle or pressing machine does not properly iron and dry all parts and some spots are left damp and perhaps wrinkled.

10 Heretofore it has been customary to iron such places with an ordinary hand iron or flat iron. This necessarily is a slow and expensive process and moreover requires the use of considerable strength.

15 One important object of the present invention is to provide an improved and novel mechanism whereby such places as have not been properly ironed in clothing subject to other ironing processes may have any un- 20 ironed or damp spots finished rapidly with less effort on the part of the operator and the obtaining of a greater production.

Furthermore, in the use of hand irons it is not practicable to employ steam and such 25 irons are generally heated by electricity or gas. The use of such irons on damp spots in clothing which has been subjected to pressing on a steam press frequently results in the burning of the dry material around the damp 30 spot on account of excessive heat applied to such dry material. That is, if the iron is hot enough to dry out the damp spots it is frequently hot enough to burn the dry part of the article. Consequently the old method of

35 hand ironing necessitated moistening a considerable area around this spot with corresponding loss of time in this operation and the ironing of the large spot thus made, the middle portion being ironed first so that the 40 iron is tempered down in such manner that when it reaches the margins of the large damp spot it will not burn the dry parts. By reason of this the time lost is considerably greater than if the damp spot itself could be ironed

45 without it being necessary to enlarge it to save scorching.

A second important object of the invention is the provision of an improved ironing finisher wherein the iron is steam heated by 50 steam of suitable temperature so that at no

time is the iron hot enough to scorch any part of the articles being ironed while at the same time the iron is amply hot to properly iron and dry the damp spot.

A third important object of the invention 55 is the provision of means for oscillating a steam heated iron on a suitable buck which can be moved from the iron for the purpose of placing the articles in position and toward the iron for bringing the latter into contact 60 with the articles, the moving of the buck being accomplished by a foot of the operator thus leaving the operator's hands free to manipulate the article being ironed.

A fourth important object of the invention 65 is to provide a machine of this character wherein the oscillation of the iron will be accomplished by an electric motor, this motor having the circuit therethrough closed, as the buck is moved into position for ironing the 70 articles and broken as the buck moves away from such position, the iron oscillating only when actually necessary to accomplish the ironing operation.

With the above and other objects in view 75 as will be hereinafter apparent, the invention consists in general of certain novel details of construction and combinations of parts hereinafter fully described, illustrated in the accompanying drawings and specifically 80 claimed.

In the accompanying drawings like characters of reference indicate like parts in the several views, and:

Figure 1 is a side elevation of the improved 85 machine.

Figure 2 is a vertical section therethrough on the median plane extending from front to rear, certain of the parts being shown in elevation.

Figure 3 is an enlarged section on the line 3—3 of Figure 1.

Figure 4 is an enlarged section on the line 4—4 of Figure 1.

Figure 5 is a section on the horizontal median line of Figure 3.

Figure 6 is a section on the line 6—6 of Figure 1.

Figure 7 is an enlarged section on the line 7—7 of Figure 1.

In the embodiment of the invention herein illustrated there is provided a base 10 which may be securely fastened to the floor or any other desirable foundation. Extending upwardly from the base is a hollow standard 11 and from the front of this standard there projects forwardly a buck supporting arm 12. Through vertically alined openings in the top and bottom of this arm extends a flat stem 13 whereon is mounted the buck and this stem has formed therein a slot 14 in which fits one end 15 of a lever pivoted between its ends on a pivot 16 extending from side to side of the hollow arm 12. The other end of this lever projects into the hollow standard 11 and pivotally connected to this end of the lever is the upper end of a link 17 which has its lower end connected to the inner end of a lever 18 mounted intermediate its ends on a pivot 19 adjacent the forward face of the lower part of the standard 11. The front end of the lever 18 is connected by a link 20 with the rear end of a pedal or foot lever 21 pivotally supported between brackets 22 on the base 10. Thus by depressing the front end of the pedal 21 the link 17 is pulled down and the lever in the arm 12 tilted so that the stem or shank 13 is lifted which thus lifts the buck supported thereon. This buck includes a hollow lower body portion 23 wherein is telescopically fitted an upper pad holding portion 24 around the lower part of which extends a spiral spring 25 so that the cover 26 of the pad 27 may be gripped by this spring and the cover thus removably held in place. The upper and lower parts are limited in movement away from each other by bolts 28 and the upper part is spring supported on springs 29 so as to accommodate varying thicknesses of articles placed thereon.

At the upper front side of the standard 11 is a bracket 30 whereon is a vertical pivot 31 on which is pivoted an operating arm 32 which carries at its forward end an iron having a vertically elongated body 33 and a flat pressing face 34 above the buck. Suitably supported from the standard and alined with the pivot 31 are forward swing joints 35, there being one of these joints above and one below the pivot. Connected to the upper joint is a steam inlet pipe 36 and an exhaust or outlet pipe 37 is connected to the lower joint, the pipes 36 and 37 leading to any suitable source of steam supply and waste respectively. Furthermore, these swing joints are connected by pipes 38 with the top and bottom of the hollow iron body 33. Thus the iron can freely oscillate on its pivot and yet be supplied with steam and the steam exhausted therefrom so that the iron can at all times be kept in a proper condition as regards heat.

Extending rearwardly from the upper portion of the standard 11 is a bracket 39 whereon is mounted a motor 40 driving a reducing gear of the ordinary worm wheel

type, the casing only of the gear being shown at 41. Extending forwardly from this reducing gear is a shaft 42 whereon is mounted a cam 43 carrying the peripheral ball bearing 44. The outer race of this ball bearing has its outer face transversely arcuate to swing between arcuate wear plates 45 fixed to the sides of a yoke 46 carried by the rear of an extension 47 of the operating arm 32, the extension 47 extending in the opposite direction to said arm from the pivot 31. This motor is connected by suitable wires indicated diagrammatically at 48 with a standard type of circuit closer or switch 49 having a pull stem or rod 50 for opening and closing the switch, the rod being pulled to close the switch and establish a circuit through the motor and pushed to break said circuit. Spaced on the rod are stops 51 which are screwed on the rod so that they may be adjusted to desired positions and projecting from the link 17 through a suitable slot in the hollow standard 11 is an arm 52 which has a yoke end 53 engaging the rod between the stops. By this means whenever the buck is raised the switch is closed and consequently the motor is set in operation and the iron oscillated. Conversely when the buck is lowered the switch is opened and the circuit through the motor is broken so that the iron will cease its oscillation.

In using the apparatus the article to be ironed is placed on the buck in such position that the spot requiring finishing is presented for action by the iron. The operator then depresses the front end of the pedal 21 and as the buck moves upwardly under this action the motor starts and the iron begins to oscillate so that the iron is oscillating as the buck reaches its operative position with the article in contact with the iron. A few seconds is sufficient to completely iron the spot unless the same is very large in which case the pedal is released, the article shifted on the buck and the pedal again depressed until the entire spot has been ironed. Then the pedal is fully released whereupon the circuit through the motor is broken and the oscillation of the iron ceases so that the device is ready for a second article, the first being, of course, removed.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In an ironing finisher, a frame, a buck

mounted on said frame for vertical movement into and out of pressing position, means for moving said buck, an iron, a supporting arm pivotally mounted on said frame and connected to the iron to restrict movement thereof to an arcuate path in a plane at right angles to the movement of the buck and in cooperation therewith, a motor having a shaft, a cam mounted on said shaft, an extension on said arm, and a yoke on said extension straddling said cam a hollow bushing in said yoke having an internal segmento-spherical surface, and a ball bearing on said cam having an outer race provided with a segmento-spherical outer surface fitting said bushing.

2. In an ironing finisher, a frame, a buck mounted on said frame for vertical movement into and out of pressing position, means for moving said buck, an iron, a supporting arm pivotally mounted on said frame and connected to the iron to restrict movement thereof to an arcuate path in a plane at right angles to the movement of the buck and in cooperation therewith, a motor having a shaft, a cam mounted on said shaft, an extension on said arm, and a yoke on said extension straddling said cam.

3. In an ironing finisher, a frame, a buck mounted on said frame for vertical movement into and out of pressing position, a stem supporting said buck, a lever pivoted intermediate its ends on said frame and having one end engaging the stem to move the same, a link depending from the other end of said lever, a pedal operatively connected to the lower end of the link whereby movement of the pedal moves the link and buck, an iron, a supporting arm pivotally mounted on said frame and connected to the iron to restrict movement thereof to an arcuate path in a plane at right angles to the movement of the buck and in cooperation therewith, a motor, means connecting the motor and supporting arm to oscillate the same, a circuit for said motor, a circuit closer in said circuit, a sliding rod for operating said circuit closer, spaced stops on said rod, and an arm projecting from said link and having a yoke engaging the rod between said stops.

50 In testimony whereof I affix my signature
CECIL H. BOYULS.
